LOOP BUCKLE

Charles A. Mosgrove, Waterbury, Conn., assignor
to The Autoyre Company, Incorporated, Oak-
ville, Conn., a corporation of Connecticut

Application October 30, 1931, Serial No. 571,951

12 Claims. (Cl. 24—73)

This invention relates to new and useful improvements in loop buckles and has particular although not exclusive relation to loop buckles of the kind used in connection with the shoulder straps of overalls for securing the shoulder straps to the overall bib portion.

An object of the invention is to provide a loop buckle, of the kind including a pair of pointed prongs to pierce a strap and thereby secure the buckle to the strap, with means to prevent casual opening of the pointed prongs of the buckle whereby in use the prongs will remain in position against a cross or guard bar and not open to catch in or tear the hands or clothing.

Another object is to provide a loop buckle comprising a partially closed loop including a cross or guard bar, a button loop pivoted on said partially closed loop, and piercing prongs formed with the button loop.

Other objects and advantages will become apparent from a consideration of the following detailed description taken in connection with the accompanying drawing wherein a satisfactory embodiment of the invention is shown. However, it will be understood that the invention is not limited to the details disclosed but includes all such variations and modifications as fall within the spirit of the invention and the scope of the appended claims to which claims reference should be had for a definition of the invention.

In the drawing:

Fig. 1 is a front elevational view showing the improved loop buckle;

Fig. 2 is a rear elevational view thereof;

Fig. 3 is a sectional view on an enlarged scale, the view being taken substantially on the line 3—3 of Fig. 1 but showing the buckle in position on the strap;

Fig. 4 is a front elevational view on an enlarged scale showing more clearly the relationship between the two members forming the buckle at their point of pivotal connection;

Fig. 5 is a view somewhat similar to Fig. 4 but with the guard member turned back into a position substantially at right angles to the prongs;

Fig. 6 is a rear elevational view showing the upper portion of a slightly modified form of the invention;

Fig. 7 is a plan view of the upper portion of the buckle showing a somewhat different construction; and

Fig. 8 is an end view of the buckle of Fig. 7 showing it in open position.

Referring in detail to the drawing my improved buckle as here shown includes a guard member

10 to which is pivotally connected a prong carrying member 11 disclosed as a button loop. The members 10 and 11 are adapted for relative pivotal movement whereby to open the buckle and permit of the attaching of the buckle to and 60 adjustment of the buckle on a strap 12 as for example a shoulder strap of a pair of overalls.

Member 10 is preferably formed from a single length of material bent to provide a partially closed loop including a top or cross bar 13 and 65 side arms 14 inclining downwardly and toward one another for a short distance as at 15 and then having their ends out turned and curled to provide loops or eyes 16. At spaced points intermediate its ends the cross bar 13 is provided with spaced indentures or depressions 17 formed by depressing portions of the material forming the bar. As the depressions or indentures 17 are formed a portion of the material at the upper edge of the bar is drawn into position to provide an overhanging flange 18 the purpose of which will later appear. Also, the portions of the material of the bar at the sides of the indentures may be shaped to provide beads 19 which together with flange 18 form a U-shaped 80 flange extending about the outer edge and sides of the indentures.

The prong carrying member 11 is also preferably formed from a single length of material as for example a length of round wire. In the 85 formation of the member 11 the wire is bent to provide a relatively small eye 20 to receive a button on the garment to be supported and connected by a restricted neck portion 21 with a relatively large eye 22. Beyond the neck 21 the 90 member 11 has its arms 23 extending in opposite directions and upwardly and these arms are then bent to provide substantially parallel vertical portions 24 from the upper ends of which the arms extend inwardly toward each other for 95 a short distance as at 25 and then incline toward each other for a short distance as shown at 26. After the portions 26 the arms are again bent into a substantially horizontal position as at 27 before being turned into vertical substantially 100 parallel relation to form the prongs 28. If desired, the prongs may have their ends cut at an angle whereby sharp points are provided.

When the members 10 and 11 are assembled it is the substantially horizontal portions 27 of 105 the member 11 that are received in the eyes or loops 16 formed at the ends of the arms of the member 10. The fit of the portions 27 in the eyes or loops 16 is such that the members 10 and 11 may have relative pivotal movement and 110

at this time attention is directed to the fact that the portions 27 are of somewhat greater length than the bearing surfaces provided by the eyes or loops 16. It will also be noted that the depressions or indentures 17 are so located as to receive the pointed ends of the prongs 28 when the members 10 and 11 are assembled and the parts positioned to dispose the ends of the prongs against the cross bar 13. In this position of the prongs their sharp or pointed ends will be covered by the lip or flange 18 and there will be no likelihood of the wearer tearing his hands or his clothing on the prongs.

Heretofore in loop buckles employing prongs the buckles become slightly worn after use and then become loose and open partially so that the ends of the prongs are exposed and liable to be caught on the hands or clothing. It will be obvious that in the present construction should any relative movement take place between the members 10 and 11 when the prongs have their ends disposed against the cross bar 13 and within the depressions 17 the ends of the prongs would be left disposed in spaced relation to the bottom of depressions 17 but their points would still be over hung or covered by the flanges 18 so that the user is not apt to catch or tear his hand on the points or catch other objects as his clothing thereon. Also according to the present invention means are provided for preventing accidental relative movement between the parts 10 and 11 when the parts in such position as to dispose the free ends of the prongs 28 against the cross bar 13 whereby said ends will remain in the depressions 17 and not be exposed or separated from the cross bar 13.

One way of providing this means is by forming notches 29 in the outer edges of the loops or eyes 16, the said notches being adapted to receive the upper portions of the inclined portions 26 of the arms of loop or member 11 when the members 10 and 11 are so positioned relatively that the prongs 28 have their ends disposed against the cross bar 13 or within the depressions or indentations 17 in said bar. As clearly shown in Fig. 5 the bottom and sides of the notches 29 are represented by a curved line. Since the member 11 is formed of wire or the like it is relatively flexible and resilient and its arms 23 may be spread apart out of their normal position and due to the inherent resiliency of the member will tend to return to normal position.

The member 11 should have the characteristic just described to permit the arms to spread apart to permit the passage of the shank of a button through the restricted neck portion 21. Further, the length of the portions 27 of the respective arms is as above pointed out somewhat greater than the length of the loops or eyes 16 or somewhat greater than the bearing surface presented by these loops or eyes and it will therefore be apparent that the arms 23 of the member 11 may spread apart an appreciable distance before the inner end portions of the prongs 28 engage the inner edges of the eyes 16.

As the member 11 is resilient and as its portions 26 enter the notches 29 when the parts or members 10 and 11 are so positioned relatively that the ends of the prongs 28 are against the bar 13 it will be apparent that the parts are yielding held in this position by coaction of the camming action of the curved edges of recesses or notches 29 against the shoulders formed by the portions 26 pressing against them by the resilient or spring action of wire 11. It will further be ap-

parent that since the member 11 is resilient an application of force to either of the members 10 or 11 in a direction to move one of said members on its pivotal connection while the other member is held against movement will result in the portions 26 of the arms riding against the curved side walls of the notches 29 in a manner to bring about a spreading apart of the arms 23.

This, of course, involves a sliding movement of the portions 27 through the eyes or loops 16 whereby the prongs are moved as for example from the dotted line position of Fig. 5 to the full line position of the figure. When one of the members 10 and 11 has been moved relative to the other the portions 26 of the arms will be engaging the straight edges or the straight portions of the outer edges of the eyes or loops 16 and the parts will remain in adjusted position. This is true since the arms of the loop member 11 will be tending to move toward or return to normal position and they will therefore grip the eyes 16.

From the foregoing it will be seen that once the buckle has been closed or the members forming the buckle adjusted to the relative positions in which they are shown in Figs. 1 through 4 they will not casually move out of such position and the pointed ends of the prongs 28 will remain against the cross bar 13 and not be in position to tear the hands or clothing. Further, since spaced depressions or indentures are provided to receive the pointed ends of the prongs if they should separate slightly from the bottom walls of depressions 17 they would still be guarded or covered by flanges 18 so as to prevent the user injuring himself on them. Also with these depressions the major portion of the member 10 remains flat and may be decorated as by swaging as shown at 31 in Figs. 1 and 4.

In the figures as thus far described the depressions or indentures 17 are partially formed by offsetting portions of the cross bar whereby said portions project slightly at the rear of the cross bar as shown at 30, see particularly Fig. 5. In Fig. 6 is shown a slightly modified construction wherein the indentures or depressions are formed without depressing the material of the bar 13 through the rear surface thereof and in this figure the rear surface of bar 13 is shown as perfectly smooth and flat.

In Figs. 7 and 8 is shown a somewhat different construction for preventing the buckle opening accidentally. In this form instead of forming a recess as at 29 to secure the camming and holding action, a lug or projection 32 is wedged on the edge of the frame at the pivot eyes or loops for the arms of the loop and prong member 11. The edges of these lugs are curved as shown at 34 so as to tend to spread the resilient arms of member 11 when it is turned on its pivot and thus resist this turning movement and tend to hold the prongs 28 in the closed position the same as in the first form.

An additional feature shown in Figs. 7 and 8 which may also be used in the form of Figs. 1 to 6 is a stop lug 35 on the opposite side of the eye or pivot loop from the cam. As shown in Fig. 8, when the buckle is open the prongs 28 engage this lug and prevent the buckle opening any further. The prongs cannot move inwardly to pass over these lugs as they are prevented from doing so by the cam surfaces engaging the shouldered or bent portions 26. If preferred the cam surfaces can be on the member 11 and cooperating with the sides of the arms of the frame.

Having thus set forth the nature of my invention, what I claim is:

1. In a buckle, a member comprising a cross bar and a pair of arms having pivot loops, a second member pivotally mounted on said first member in said loops and including a pair of prongs movable between a position against and a position spaced from said cross bar as the members are pivoted relatively, and means on the edges of said loops engaging the other member to hold said members against casual relative movement when the prongs are against the cross bar. 80
2. In a buckle, a member comprising a cross bar and a pair of arms having pivot loops, a second member pivotally mounted on said first member in said loops and including a pair of prongs movable between a position against and a position spaced from said cross bar as the members are pivoted relatively, and cams on the edges of the loops to engage the other member for holding the members against casual relative movement when the prongs are against the cross bar. 85
3. In a loop buckle, a member comprising a cross bar and a pair of arms, a second member pivotally mounted on said first member, said second member including a pair of spaced relatively movable arms having their free ends disposed in substantially parallel relation to provide a pair of prongs, said prongs movable between a position against and a position spaced from the cross bar as the members are pivoted relatively, means preventing casual pivotal movement between the members when the prongs are against the cross bar, and the arms of the second member adapted to be spread apart to permit of pivotal movement of one of the members relative to the other thereof when the prongs are against the cross bar. 90
4. In a loop buckle, a member comprising a cross bar and a pair of arms extending from the cross bar, another member having a pair of arms with their free end portions arranged to provide a pair of prongs, one of said members including a pair of loops formed by its arms, the other of said members having portions of its arms arranged in said loops whereby the members are pivotally connected, said members movable relatively to locate said prongs against the cross bar or in spaced relation thereto, one of said loops having a notch in its outer edge, and the arm passing through said loop having a portion to enter said notch and secure the members together against casual relative movement when the prongs are against the cross bar. 95
5. In a loop buckle, a member comprising a cross bar and a pair of arms extending from the cross bar, another member having a pair of arms with their free end portions arranged to provide a pair of prongs, said first member including a pair of loops formed by the end portions of its arms, the other of said members having portions of its arms arranged in said loops whereby the members are pivotally connected, said members movable relatively to locate said prongs against the cross bar or in spaced relation thereto, each of said loops having a notch in its outer edge, and the arms passing through said loops having a portion to enter said notches and secure the members together against casual relative movement when the prongs are against the cross bar, and said arms adapted to spread apart to move said portions out of the notches on the application of force to move the members relatively. 100
6. In a loop buckle, a member comprising a cross bar and a pair of arms, a second member pivotally mounted on said first member and including a pair of prongs movable between a position against and a position spaced from said cross bar as the members are pivoted relatively, means to receive the points of the prongs when the prongs are against the cross bar, said means including a pair of spaced open faced indentures whereby the major portion of the cross bar remains and may be ornamented, and a U-shaped flange extending about the outer edge and the sides of each of said indentures. 105
7. In a loop buckle, a member comprising a cross bar and a pair of arms extending from the cross bar, a button loop pivotally connected with the member, said button loop comprising a length of wire bent to provide a relatively large eye, a relatively small eye, a restricted neck portion connecting said eyes and a pair of prongs, said member and button loop movable one relative to the other on said pivotal connection whereby to dispose the ends of the prongs against the cross bar or in spaced relation thereto, and means at the pivotal connection between the member and loop for holding them against casual relative movement on their pivotal connection when the prongs are against the cross bar. 110
8. In a loop buckle, a body member having pivot loops, a web securing member having resilient arms pivoted to the body member by passing through said loops, said arms connected at one side of said loops and sharpened at the other sides thereof and forming web penetrating and holding prongs, and camming surfaces on edges of the loops engaging said arms and cooperating therewith to tend to hold the securing member in web securing position. 115
9. In a loop buckle, a body member having pivot loops, a web securing member having arms pivoted to the body member by passing through said loops, said arms connected at one side of said loops and sharpened at the other sides thereof and forming web penetrating and holding prongs, camming surfaces on edges of said loops to engage the other member, and one of said members being resilient to cooperate with said cam surfaces to tend to hold the securing member in web holding position. 120
10. In a loop buckle, a body member having arms providing pivot loops, a resilient web holding member having portions pivoted in said loops, cam surfaces on the edges of said loops cooperating with said portions to retain the holding member in holding position, and a stop shoulder on said loops to engage the holding member to limit relative movement between the members. 125
11. In a loop buckle, a body member having arms providing pivot loops, a resilient web holding member having portions pivoted in said loops and prongs to hold the web, cam surfaces on certain edges of the loops to cooperate with said pivoted portions to retain the web holding member in holding position, and lugs on other edges of the loops to engage the prongs and limit their movement toward open position. 130
12. In a loop buckle, a body member having arms providing pivot loops, a resilient web holding member having portions passing through and pivoted in said loops, said portions connected at one side of said loops and extending in spaced relation at the other sides thereof and comprising web penetrating and holding prongs and cam surfaces on the edges of said loops cooperating with said portions to retain the holding member in holding position. 135
13. In a loop buckle, a body member having arms providing pivot loops, a resilient web holding member having portions pivoted in said loops and prongs to hold the web, cam surfaces on certain edges of the loops to cooperate with said pivoted portions to retain the web holding member in holding position, and lugs on other edges of the loops to engage the prongs and limit their movement toward open position. 140
14. In a loop buckle, a body member having arms providing pivot loops, a resilient web holding member having portions pivoted in said loops and prongs to hold the web, cam surfaces on certain edges of the loops to cooperate with said pivoted portions to retain the web holding member in holding position, and lugs on other edges of the loops to engage the prongs and limit their movement toward open position. 145
